UNITED STATES PATENT OFFICE.

HENRY M. NESTOR, OF OMAHA, NEBRASKA.

GAME APPARATUS.

Application filed March 29, 1927. Serial No. 179,309.

This invention relates to game apparatus and more particularly to a device of this character employing a plurality of rolling spheres operating in parallel trackways to simulate racing and similar sports.

An important object of the invention is to so construct the trackway that the actual length thereof is considerably shortened without shortening the effective length and the parallel trackways may conveniently be formed of the same length.

A further object of the invention is the provision in a device of this character of a convenient means whereby the spheres employed in the parallel trackways may be simultaneously released and the sphere first arriving at its destination may be positively identified.

A further and more specific object of the invention is to provide means for positively indicating not only the sphere which first arrives at its destination, but likewise the trackway in which said sphere was traveling.

Other objects and advantages will appear throughout the course of the following description.

My invention is illustrated in the accompanying drawings, wherein:—

Figure 1 is a side elevation of a game apparatus constructed in accordance with my invention;

Figure 2 is a plan view thereof, the starting hopper being removed;

Figure 3 is an enlarged vertical sectional view of the starting hopper;

Figure 4 is a perspective view of the mechanism of the indicator;

Figure 5 is a vertical sectional view through the indicator;

Figure 6 is a detail sectional view showing the spring which operates the starting mechanism when released;

Figure 7 is a side elevation showing a slightly modified form of trackway;

Figure 8 is an end elevation of the form of trackway shown in Figure 7.

Referring now more particularly to the drawings, the game apparatus includes a plurality of parallel trackways 10, 11 and 12, each of which is formed in a plurality of sections. In the present illustration, the corresponding sections of the trackways are connected to one another in units 13, 14 and 15, and these units are arranged in superposed relation. Each unit is inclined from

end to end and has its lower end overlying or adjacent to the upper end of the unit next below. Means generally designated at 16 are employed for directing a sphere 17 travelling in any section of a trackway into the corresponding section of the trackway of the unit next below.

In Figure 1, adjacent sections of the trackway are decussate and the connections 16 comprise arcuately curved plates 18 having grooves 19 formed in the continuations of the trackway. By an inspection of this figure, it will be noted that a trackway, which discharges into the outer groove 19 of one of an upper plate 18, will, when it arrives at the next plate 18, discharge into the inner groove thereof. In this manner, the travel of the spheres 17 is compensated for in such manner that the effective length of the trackway sections and the connection grooves 19 between these sections is the same for any given trackway. This is true without regard to the number of trackways which may be employed.

In Figure 7, the trackway sections 13 directly overlie one another and the connections are in the form of arcuate vertically extending tongues 20 against which a sphere, leaving a trackway 10, 11 or 12 of an upper section, impinges and is deflected into the corresponding trackway of the section next below. With this construction, the trackway sections directly underlie one another and it will be obvious that the actual distance through which the sphere must travel in the parallel trackways is equal. The decussate construction is, however, preferred, in that it permits a more ready inspection of the travel of the spheres in the trackways.

In combination with a structure of this character, I provide a means 21 for simultaneously depositing in the upper end of the upper section of each trackway a sphere 17 and a means 22 located at the lower end of the lower section of the trackways for indicating which sphere 17 is first to complete its journey. The means 21 comprises a casing including a plurality of open-bottomed pockets 23, one above each trackway 10, 11 and 12. The bottoms of these pockets are formed by the trackways 10, 11 and 12 and the casing has its side wall 24 next adjacent the lower end of the upper section 13 of the trackway sufficiently spaced from the trackways to permit the balls to escape from the pockets.

Extending transversely of the trackways and mounted at its ends in the walls of the casing is a shaft 25 having secured thereto stop plates 26 corresponding in number and arrangement to the trackways. These stops 26, in one position of the shaft, obstruct the openings formed by the abbreviation of the wall 24 and permitting escape of the spheres from the compartments 23, and in the second position thereof will permit escape of the spheres from the pockets. A spring 27 connecting the shaft 25 with the wall of the casing 21 constantly urges the shaft to the last named position. The shaft 25 has secured thereto a crank arm 28 having projecting therefrom a pin 29. This pin coacts with one arm 30 of a bell crank latch 31, the opposite arm 32 of which is urged by a spring 33 to a position such that the bill 34 of the latch overlies the pin 29 and serves to hold the arm 28 and shaft 25 in a position where the plates 26 obstruct movement of the spheres against the action of the spring 27. A link 35 is secured to the arm 32 and projects through the upper wall of the casing, where it is provided with an operating head 36. This link has a lug 37 engaging the inner wall of the casing when the link is elevated to a predetermined degree to limit upward movement of the link and position the bill of the latch in such manner that the pin, during rotation of the shaft 25, will engage against a cam face 38 formed upon the upper surface of the bill and thus wedge the bill aside to permit passage of the pin 29 to the locking position. Movement of the arm 28 to the releasing position is limited by a stop lug 39 carried by the casing and the pin 29 preferably extends through an accurate slot formed in the casing wall to provide an operating handle at the exterior of the casing, whereby the shaft may be rotated. It will be obvious that when the plates are in the pocket closing position, the spheres may be placed therein and a simultaneous release thereof may be effected by the pressing of the head 36 to permit the spring 27 revolve the shaft 25 and move the plates 26 to their inoperative position.

The indicating mechanism 22 includes a casing in the side walls 40 of which are rotatably mounted the ends of a pair of parallel shafts 41 and 42. The outer ends of the shaft 41 is provided with a crank handle 43, by means of which it may be oscillated. Rotatably mounted upon the shaft 41 are indicating disks 44 corresponding in number and arrangement to the trackways 10, 11 and 12. Each indicating disk has an indicator, at present illustrated as a tab 45 numbered to correspond to the trackways and these tabs in one position of the disk project through slots 46 formed in the casing wall and are visible. The disks are constantly urged to this position by means of

springs 47. Each disk has outstanding therefrom a lug 48, the purpose of which will hereinafter appear and adjacent this lug, the outer face of the disk is formed with a cam surface 49.

Mounted upon the shaft 42 are levers 50, each lever having one end thereof underlying the associated disk and this end is provided with a downward extension 51 carrying a paddle 52 obstructing the associated trackway 10, 11 or 12. The opposite arm of the lever is bent intermediate its ends, so that its terminal portion 53 extends vertically and to these terminal portions springs 54 are secured, which constantly urge the terminal portions away from the disk 44 and into engagement with stops 55. This movement of the terminal portion causes the end of the lever underlying the disk to move upwardly toward the disk, so that a notch 56 formed therein may receive the outer end of the lug 48. A control bar 57 is provided, which extends between the upper ends of the terminal portions 53 of the levers 50 and the adjacent disks. The ends of this bar are downbent at 58 and rotatably engaged with the shaft 42. Springs 59 constantly urge the control bar toward the peripheries of the disks 44 and the movement of the control bar in this direction is limited by a stop 60 carried by the casing wall. The shaft 41 has secured thereto adjacent each disk and at that side of the disk bearing the lug 48 a spring arm 61 which, when the shaft 41 is rotated, will come into engagement with the lugs 48 of the disk and cause the disks 44 to be rotated against the action of the springs 47 until they arrive at a position where the lugs 48 engage in the notches 56 of the levers 50. With the disks in this position, the first sphere to engage against the associated paddle 52 will cause the lever 50 associated therewith to rock sufficiently to release the lug 48 and permit the disk 44 to be rotated by its spring 21. This will bring the tab 45 into signalling position and will cause the cam face 49 of the disk 44 to engage against the control bar 57 and urge the same away from the stop 60 until it is wedged between the terminal portions 53 of the levers and the cam. Since the terminal portions 53 are limited in their movement by the stop 55, it follows that none of these levers may be oscillated upon the pivots thereof, so that spheres arriving later than the first sphere will strike against their paddles 52 without affecting the levers. If a tie between two spheres results, the signals of both spheres will be moved to indicating position. To restore the disks to their proper position, it is simply necessary to manipulate the crank 43 a sufficient distance to bring the lugs of the disks into locking position.

It will be obvious that with apparatus of this character, many different games can be played. The spheres can be considered as persons or animals participating in a race or game. Due to the fact that varying weather conditions and the collection of small particles of dust or similar obstacles in the trackways will cause a variation in the speed attained by the spheres in different tracks, the result is always uncertain, so that the apparatus will afford considerable amusement. It will also be obvious that the signalling mechanism may be removed where it is desired to allow the spheres to roll out upon a surface when playing games where the distance instead of the speed determines the winner.

Since the construction of the apparatus is obviously capable of a certain range of change and modification without materially departing from the spirit of the invention, I do not limit myself to such specific structure except as hereinafter claimed.

I claim:—

1. In game apparatus, a plurality of trackways of the same length and identical inclination, means at the upper end of the trackways for simultaneously releasing therein objects which will move by gravity from the upper to the lower end thereof and means at the opposite end of the trackways and actuated by the passage of an object moving along any of the trackways for positively barring the subsequent passage of an object along any of said trackways.

2. In game apparatus, a plurality of trackways of the same length and identical inclination, means at the upper end of the trackways for simultaneously releasing therein objects which will move by gravity from the upper to the lower end thereof, means at the opposite end of the trackways for positively indicating which of articles so released is first to arrive at its destination, said trackways being formed in sections, said sections being superposed and means conducting an article leaving the lower end of any section of a trackway into the upper end of the trackway section next beneath, said means preserving the uniform length of the trackways.

3. In game apparatus, a plurality of trackways of the same length and identical inclination, means at the upper end of the trackways for simultaneously releasing therein objects which will move by gravity from the upper to the lower end thereof, means at the opposite end of the trackways for positively indicating which of articles so released is first to arrive at its destination, said trackways being formed in sections, said sections being superposed and means conducting an article leaving the lower end of any section of a trackway into the upper end of the trackway section next beneath,

said means preserving the uniform length of the trackways, adjacent sections of the trackway being decussate.

4. In game apparatus, a plurality of trackways of the same length and identical inclination, means at the upper end of the trackways for simultaneously releasing therein objects which will move by gravity from the upper to the lower end thereof, means at the opposite end of the trackways for positively indicating which of articles so released is first to arrive at its destination, said trackways being formed in sections, said sections being superposed and means conducting an article leaving the lower end of any section of a trackway into the upper end of the trackway section next beneath, said means preserving the uniform length of the trackways, adjacent sections of the trackway being decussate, the connections between said sections comprising arcuately curved plates having parallel grooves formed therein providing continuations of the trackways.

5. In game apparatus, a plurality of parallel trackways of the same length and identical inclination, a casing overlying the upper ends of the trackways and having a pocket for each trackway, the bottom of which opens to the trackway, a rock shaft extending through the casing and transversely of the trackway, plates secured to the shaft, means for rotating the shaft from a position where said plates obstruct passage down the trackways of articles placed in the pockets to a position where the escape of the articles from the pockets is permitted, a spring constantly tending to rotate the shaft in the last named direction and means for latching the shaft in the first named position and means at the lower ends of the trackways to indicate which of the articles released at the upper ends of the trackways is first to arrive at its destination.

6. In game apparatus, a plurality of parallel trackways of the same length and identical inclination, a casing overlying the upper ends of the trackways and having a pocket for each trackway, said pockets communicating with the trackway, means within the casing movable to a position where it obstructs communication between the pockets and the trackways or to a position where it permits such communication, a latch for retaining said means in the first named position and a spring constantly urging said means to the last named position.

7. In game apparatus, a plurality of parallel trackways of the same length and identical inclination, a casing overlying the upper ends of the trackways and having a pocket for each trackway, said pockets communicating with the trackway, means within the casing movable to a position where it obstructs communication between the pockets

and the trackways or to a position where it permits such communication, a latch for retaining said means in the first named position, a spring constantly urging said means to the last named position, means operable at the exterior of the casing for moving the shaft from the last to the first named position to permit its engagement by said latch and means operable at the exterior of said casing for releasing said latch.

8. In game apparatus, a plurality of parallel trackways of the same length and identical inclination, means at the upper ends of the trackways for simultaneously releasing therein objects which will move by gravity from the upper to the lower end thereof, a casing at the lower end of the trackways and into which the lower end of the trackways discharge, a plurality of rotatable indicators within the casing and having bias normally moving them to indicating positions, a latch associated with each indicating mechanism and operated to release the associated indicating mechanism to permit its movement from non-indicating to indicating position when engaged by an object moving in the trackway and means operated by the movement of an indicator from non-indicating to indicating position for locking the latches against operation by objects moving in the trackways.

9. In game apparatus, a plurality of parallel trackways of the same length and identical inclination, means at the upper ends of the trackways for simultaneously releasing therein objects which will move by gravity from the upper to the lower end thereof, a casing at the lower end of the trackways and into which the lower end of the trackways discharge, a plurality of rotatable indicators within the casing and having bias normally moving them to indicating positions, a latch associated with each indicating mechanism and operated to release the associated indicating mechanism to permit its movement from non-indicating to indicating position when engaged by an object moving in the trackway, means operated by the movement of an indicator from non-indicating to indicating position for locking the latches against operation by objects moving in the trackways, and means operable from the exterior of the casing for rotating the indicators from indicating to non-indicating position.

10. In game apparatus, a plurality of parallel trackways of the same length and identical inclination, means at the upper ends of

the trackways for simultaneously releasing therein objects which will move by gravity from the upper to the lower end thereof, a casing at the lower end of the trackways and into which the lower end of the trackways discharge, a plurality of rotatable indicators within the casing and having bias normally moving them to indicating positions, a latch associated with each indicating mechanism and operated to release the associated indicating mechanism to permit its movement from non-indicating to indicating position when engaged by an object moving in the trackway, means operated by the movement of an indicator from non-indicating to indicating position for locking the latches against operation by objects moving in the trackways, and means operable from the exterior of the casing for rotating the indicators from indicating to non-indicating position, each of said indicators including a lug coacting with the associated latch, the last named means comprising a rotatable shaft forming the axis upon which said indicators rotate and having arms corresponding in number and arrangement to the indicators and adapted to engage the lugs thereof when the shaft is rotated.

11. In game apparatus, a plurality of parallel trackways of the same length and identical inclination, means at the upper ends of the trackways for simultaneously releasing therein objects which will move by gravity from the upper to the lower end thereof, a casing at the lower end of the trackways and into which the lower end of the trackways discharge, a plurality of rotatable indicators within the casing and having bias normally moving them to indicating positions, a latch associated with each indicating mechanism and operated to release the associated indicating mechanism to permit its movement from non-indicating to indicating position when engaged by an object moving in the trackway, each of said latches including a part moving toward the periphery of the indicator as the latch is moved to release the indicator, means limiting movement of said portion of the latch in the opposite direction and means interposed between said portions of the latches and said indicators and clamped between the periphery of the indicator and said portions of the latches when an indicator is in indicating position.

In testimony whereof I hereunto affix my signature.

HENRY M. NESTOR.
